L. M. WHITMAN, OF STERLING, ILLINOIS, ASSIGNOR TO HIMSELF
AND A. B. ENDERTON, OF THE SAME PLACE.

Letters Patent No. 83,746, dated November 3, 1868.

IMPROVED INVALID-CHAIR.

The Schedule referred to in these Letters Patent and making part of the same.

To all whom it may concern:

Be it known that I, L. M. WHITMAN, of Sterling, in the county of Whitesides, and State of Illinois, have invented a new and improved Invalid-Chair; and I do hereby declare that the following is a full, clear, and exact description thereof, which will enable others skilled in the art to make and use the same, reference being had to the accompanying drawing, forming part of this specification.

This invention relates to chairs which are made convertible into other forms, and so constructed that the position of the occupant may be changed at will, and the chair be made to rock or not, as may be desired.

The invention consists in making in sections back, seat, front, and foot-piece, and operating them by means of a transverse shaft, and cords and pulleys, and a lever upon each side, with other appropriate fixtures in connection therewith, as will be hereinafter more fully described.

The drawing represents the chair in two different positions; one, as a chair with upright or inclined back, with the parts shown in red color; the other position represents it as a couch, the standards and movable parts being seen in either red or dark lines, as they appear when the chair is in the position indicated.

A is the back;

B is the seat;

C is the front; and

D is the foot-piece.

The seat is stationary, and is suitably supported on legs, which are attached to rockers, E.

The back and the front are hinged to the seat, and the foot-piece is hinged to the front, so that they may be readily adjusted to the required positions.

Immediately back and below the seat, supported by arms, F, from the back legs G of the seat, there is a horizontal shaft, upon the ends of which are crank-wheels, H, with ratchet-teeth upon their peripheries, and with pawls, I, arranged so as to hold the wheels H from turning back.

J represents levers, (one on each side of the chair,) which are attached to the seat B by pins, K, so that the ends may rise and fall, as required.

L represents cords, (one on each side,) the ends of which are attached to the ends of the levers or bars J, as seen in the drawing. Starting from the point m the cord (upon the side in view) passes down under a pulley, n, on the rocker, and then upward to the shaft, through which it passes, and is secured thereto so that it cannot slip. From the shaft it is passed downward around another pulley, o, on the rocker, and then upward, and is attached to the other end of the lever J, as seen at p.

The cord is so secured to the shaft that when the shaft is revolved, it winds on from one direction, thereby depressing one end of the lever J, and winds off from the shaft in the other direction, and thereby raising the other end of the lever.

There are pins, as indicated by the letter q, on each side of the chair, which are taken out of holes, or inserted, as the chair is changed from one position to another. When the shaft is turned so that the end of the lever, which is marked r, is depressed, it will be seen that the back of the chair will be drawn down, as that end of the lever is attached to the back by a pin, S, which works in a slot.

The pin q, at the other end of the lever, also works in a slot, so as to accommodate the movement of the front, C, when it is raised or lowered.

When the chair is converted into a couch, as represented, the lever J will occupy a nearly horizontal position, as seen in the drawing.

For the purpose of holding the chair in this position, and prevent rocking, there are standards, T, at the front, and U at the rear, which are pivoted to the rocker on each side, as seen at V.

The standard T is double, so that when in an upright position the lower end is in contact with the floor, while both the foot-piece D and the front, C, are supported by it.

The back standard U also serves a similar purpose in bearing upon the floor at the lower end to prevent rocking, and supporting the back at the upper end, as seen in the drawing.

A person occupying the chair may, by turning the crank-wheels H, (and consequently the shaft,) and properly arranging the pins, change it to any desired position.

W represents a truck, which is attached to the front stand T, in any suitable manner, in case it is found necessary to move an invalid from one room to another.

The back standard U is fixed by the pin q in the position seen in the drawing, so that the back portion of the chair may be raised from the floor, and the weight thrown upon the truck-wheels.

X represents detachable arms, for the sides of the chair, which may be used as occasion may require.

Having thus described my invention,

I claim as new, and desire to secure by Letters Patent—

1. The combination of the pivoted, slotted bar J, cord L, pulleys o n, rocker E, shaft and crank-wheels H, and the standards T U, with the back, A, seat B, front, C, and foot-piece D, substantially as described, for the purpose specified.

2. In combination with an invalid's chair, the adjustable stands T and U, arranged substantially as shown and described for the purposes set forth.

3. In combination with an invalid's chair and the stands T and U, the truck W, substantially as and for the purposes set forth.

L. M. WHITMAN.
